UNITED STATES PATENT OFFICE

2,468,797

METHOD OF MAKING PREFORMED PACKING

James T. Wong, Vallejo, Calif.

Application June 8, 1945, Serial No. 598,346

2 Claims. (Cl. 154—33.1)

(Granted under the act of March 3, 1883, as amended April 30, 1928; 370 O. G. 757)

1

This is a divisional application of Serial No. 559,105 filed October 17, 1944, Patent No. 2,441,177, entitled "Preformed packing making machine."

This invention relates to a method for making preformed packing and has for an object to provide a suitable method for the manufacture of preformed packing.

A further object of this invention is to provide an inexpensive and simple method utilizing a machine which is pedal-operated for making preformed packing, the packing being especially intended for use in electric cable stuffing tubes, eliminating the necessity for the previous method of hand packing the stuffing tube about electric cable. Hand packing of electric cable stuffing tubes is eliminated on new installations by inserting preformed bulkhead tube packing made, according to this invention, through the tubes before the cables are installed.

A further object of this invention is to provide a method for making preformed packing suitable for use in glands or stuffing tubes of any nature.

With the foregoing and other objects in view, the invention consists in the construction, combination and arrangement of parts hereinafter set forth, claimed and illustrated in the drawings in which:

Fig. 1 is a perspective view of the preformed packing making machine of this nature.

Fig. 2 is a sectional fragmentary view on line 2—2 of Fig. 1.

Fig. 3 is a sectional partly fragmentary view on line 3—3 of Fig. 1.

Fig. 4 is a sectional view on line 4—4 of Fig. 3.

Fig. 5 is an enlarged partly sectional fragmentary view showing the completed packing ready to be discharged, and

Fig. 6 is a perspective sectional view of the packing made according to the method of this invention.

There is shown at 10 the packing making machine of this invention which includes a table 11 supported on legs 12 having foot plates 13. The side legs 12 are connected by braces 14 which in turn support a cross brace 15. Mounted on the table 11 is a pair of vertical beams 16 which in turn rigidly support a bridge plate 17. Adjustably and fixedly secured to this bridge plate 17 by means of a threaded end 18 is a mandrel 20, the mandrel extending vertically downward and being adjusted in position to terminate just above the surface of the table 11 over a suitable opening 21 in the table 11. Supported on the table 11 is a plate 22 having a gateway 23 therein, wherein is slidably

supported a gate 24 adapted to be moved to open and close the table opening 21. The gate 24 is movable to open and close table opening 21 by means of a lever 25 pivoted to the plate 22 at 26 at one end and provided with an operating handle 27 at the other end.

Supported over the table opening 21 by means of a flange 28 is a cylinder 30 surrounding the lower end of mandrel 20. The inner diameter of the cylinder 30 is greater than the diameter of the mandrel 20 by an annular amount substantially equal to the annular thickness of the preformed packing 31 shown in Fig. 5 which is made therein.

An annular plunger 32 of a size to slidably fit about mandrel 20 and into the cylinder 30 is supported on the cross strips 33 of a vertically movable platform 34 adjustably mounted on the vertically movable rods 35. These rods at their upper ends extend through the bridge plate 17, being provided with nuts 36 for adjustably limiting their upward movement. Pistons 37 secured at the upper ends of rods 35 on top of coil springs 38 within spring tubes 40 serve to keep the rods 35 at the top limit of their movement permitted by the adjusting nuts 36 beneath the bridge plate 17. The lower ends of rods 35 extend through suitable openings in the plate 22 and table 11 and end in inturned fingers 41 extending into a triangular lever 42 whose apex 43 is pivotally secured to a foot lever 44 having a pivotal connection 45 on the cross brace 15. The other end of lever 44 is provided with a foot pedal 46. Obviously this machine can be modified to be power operated instead of pedal operated.

In operation the springs 38 normally hold the plunger 32 at the upper limit of its movement. When in this position, packing material is manually wound about that portion 20' of the mandrel 20 which is visible between the top of cylinder 30 and the bottom of plunger 32. In one form of packing made by this machine a strip of packing 50 of card consistency is first wound about the mandrel portion 20' and then foot pedal 46 is depressed, causing plunger 32 to force this first portion of packing 50 into the annular space between the bottom of the mandrel 20 and the inside of cylinder 30 on top of gate 24. The pedal 46 is released, permitting the plunger 32 to be raised by the springs 38 to its original position. A packing 51 of softer consistency is then wound about the mandrel portion 20' and then compressed against the first portion only within cylinder 30. A third portion of packing material 52 of a consistency similar to the first portion is then placed on the

mandrel portion 20' and compressed against the previously compressed portions of packing. The packing 31 is thus completed and then the handle 27 is grasped to cause the lever 25 to open the gate 24 whereupon the pedal 46 is depressed again, causing the completed packing 31 to be discharged through the table opening 21, whereupon the machine is empty, ready for a new preformed packing to be made thereon. As will be apparent, the mandrel 20, the cylinder 30 and the plunger 32 are easily removable and replaceable and may be replaced by similar articles of somewhat different size, thus making it possible to make packing of various sizes on the same machine by merely substituting an appropriately sized mandrel, plunger and packing.

Other modifications and changes in the number and arrangement of the parts may be made by those skilled in the art without departing from the nature of this invention, within the scope of what is hereinafter claimed.

The invention herein described and claimed may be manufactured and used by or for the Government of the United States of America for governmental purposes without the payment of any royalties thereon or therefor.

What is claimed is:

1. A method of preforming a packing comprising spirally winding a strip of hard packing about a mandrel into a cylindrical form, applying pressure axially of the cylindrical form while confining it against deformation, spirally winding a strip of soft packing about the same mandrel into a cylindrical form and placing it axially of the first formed packing portion, applying pressure axially of the soft packing form against the hard packing form while confining both packing portions together against deformation, then spirally winding a hard packing about the same mandrel into a cylindrical form and moving it axially against

the soft packing form by applying pressure axially thereagainst to complete the packing and confining the completely formed packing against deformation while the axial pressure is applied and thereafter releasing the completely formed packing from the mandrel and from confinement.

2. A method of preforming a packing comprising spirally winding a strip of packing about a mandrel into a cylindrical form and applying pressure axially of the cylindrically formed packing while confining it against deformation, then spirally winding a strip of softer consistency about the same mandrel into cylindrical form above the first-formed strip and applying pressure axially thereof while continuing to confine it against deformation, then spirally winding a third strip similar to the first strip about the same mandrel into similar form against the top of the strip of softer consistency and again applying pressure while confining it against deformation and thereafter removing the packing from the mandrel and from confinement.
